CLAIM

The ornamental design for a set of footwear as shown and described.

DESCRIPTION

The patent or application file contains at least one drawing executed in color. Copies of this patent or patent application publication with color drawing(s) will be provided by the Office upon request and payment of the necessary fee.

FIG. 1 is a right-side perspective view of the right foot of a set of footwear showing my new design;

FIG. 2 is a top view of the set of footwear;

FIG. 3 is a back perspective view thereof;

FIG. 4 is a bottom perspective view of the right foot of the set of footwear;

FIG. 5 is a right-side perspective view of the right foot of a second embodiment of a set of footwear showing my new design;

FIG. 6 is a top view of the second embodiment of the set of footwear;

FIG. 7 is a back perspective view thereof; and,

FIG. 8 is a bottom perspective view of the right foot of the second embodiment of the set of footwear.
